UNITED STATES PATENT OFFICE.

ROBERT V. CHEATHAM, OF ST. MATTHEWS, AND ELMER S. OLMSTED, OF LOUISVILLE, KENTUCKY, ASSIGNORS TO CHEATHAM ELECTRIC SWITCHING DEVICE COMPANY, OF LOUISVILLE, KENTUCKY, A CORPORATION OF KENTUCKY.

AUTOMATIC SWITCHING DEVICE.

1,239,258.

Specification of Letters Patent. Patented Sept. 4, 1917.

Application filed August 31, 1916. Serial No. 117,824.

To all whom it may concern:

Be it known that we, ROBERT V. CHEATHAM and ELMER S. OLMSTED, citizens of the United States, and residents of St. Matthews and Louisville, county of Jefferson, and State of Kentucky, have invented a new and useful Improvement in Automatic Switching Devices, of which the following is a specification.

10 The object of our invention is to produce an improvement in the switching devices shown in the earlier Cheatham Patents Nos. 612,702, 787,827 and 917,541, as well as other patents which it is not necessary to mention. 15 In each of these patents is disclosed a trolley pan on a trolley wire, a relay or controlling magnet, a double solenoid with a core connected to the switchpoint rail, and the necessary wiring, so that when the device is in 20 use with power on the motors of the car operating the switch, the switchpoint is always and invariably thrown in one direction, and when power is off the motors of the car, the switchpoint is always and invariably thrown in the other direction. 25 When carrying out the invention as shown in the first and last above mentioned patents, there has been trouble when a trolley wheel has stood under the trolley pan, because under such circumstances magnets have been 30 burned out, or fuses have been burned out, causing unnecessary annoyance and inconvenience. To partially overcome this trouble the device shown in Patent No. 787,827 was 35 invented. The invention of this device entirely overcame the burning out trouble, but it causes the switch to always be thrown in the way it is thrown when current is on the motors when the car is stopped. 40 Another trouble has been that one car will follow another too closely and so, at times, the forward wheels of a car will be placed on one track and the rear wheels on another, and derailment is sure to ensue unless the 45 car is promptly stopped. The object of our present invention is to overcome all difficulties above enumerated, as will appear below.

For a more particular description of our 50 invention, reference is to be had to the ac-

companying drawings, forming a part hereof, in which—

Figure 1 is a diagrammatic view of our improved system.

Figs. 2 and 3 show a cut-out used in this 55 system, Fig. 3 being a sectional view of the structure shown in Fig. 2.

Throughout the various views of the drawings, similar reference characters designate similar parts.

Our improved system 1 is provided with the ordinary trolley pan 2, which may be of any suitable kind, the relay 3, which may be of the conventional form such as has long been used, the double solenoids 4 and 5, the 60 core 6 and the switchpoint rail 7, which parts have always been found in one form or another in each form of switch patented by Cheatham, as above set forth. The magnet 8 and the relay 3 receive electricity from a 65 wire 9 that runs to a trolley wire 10 and delivers electricity to a wire 11 that runs to one bar 12 of the trolley pan 2. The other bar 13 of this trolley pan 2 is connected to a wire 14 which runs to a contact 15 of a 70 cut-out 16, which will be described more in detail below. The switch blade 17 of the cut-out 16 is connected to a wire 18 that runs to a contact 19 of a second cut-out 20, which will be described more in detail below. At 75 this time it is sufficient to say that the armature 21 of this second cut-out connects the contact 19 with the contact 22, as shown in Fig. 1, under certain conditions, and the contact 22 is connected by a wire 23 to the 80 armature 24 of the magnet 8. This armature 24 may be a weight armature, or be provided with a spring 25, as shown, or be both a weight and spring armature. Weight armatures have the advantage of being sure, and 85 spring armatures have the advantage of being quick. By combining a weight and spring with the same armature, one gets both advantages.

The armature 24 normally rests on a contact 26 but does not so rest when the magnet 8 is energized by a motor current, as then this armature is raised until it is in contact with the contact 27. These contacts are connected to the ground solenoids 5 and 4 by 90 100

- the wires 28 and 29 respectively. It is apparent from what has been said that either one, but not both at the same time, of these ground solenoids 4 and 5 may be energized.
- 5 It is also apparent that the one which is energized will be determined by whether or not motor power is applied through the trolley wheel 30 while it connects the bars 12 and 13 of the trolley pan 2.
- 10 It will be noted that the bar 13 is not as long as the bar 12 but is supplemented by two end bars 31 and 32, both of which help to guide the trolley wheel in the conventional way. The bar 31 is, electrically speaking, dead, while the bar 32 is alive when the trolley wheel 30 connects it with the bar 12, and at no other time. In other words, the bar 31 could be made of insulating material, while the bar 32 must be made 15 of a conducting material.
- 15 From the foregoing it is apparent that when the trolley wheel 30 is in place, as shown, and power off the motors the switch-point is thrown in one direction, and when power is on the motors the switch-point is thrown in the other, and which way is determined by the motorman through his controller. If, for any reason, he has to stop while the trolley wheel 30 connects the bars 20 12 and 13, the cut-out 16 will act in a manner which will now be described.
- 20 The wire 14 is connected to a wire 33 in which is interposed a suitable resistance 34^a, which wire 33 runs to a magnet 34 of the cut-out 16, and from thence another wire 35 runs to the ground 36. The magnet 34 is incased in a suitable casing 37 mounted in a switch-box or other suitable structure, and this casing 37 is about a non-magnetic tube 38, which is preferably made of hard rubber, and is fixed in the casing 37. It is covered at its lower end by a suitable covering 39. In this tube 38 runs a magnetic core 40, which at its upper end carries a brass rod 41, which runs through a cover 42, and this rod 41 is weighted by a weight 43 which is carried thereon in any way and a quantity of mercury is placed in the tube 38. The upper end of the rod 41 is passed through a 45 guide 44, and a pin 41^a therein engages an arm 45 which is pivoted at 46 and fixedly connected to the switchblade 17 so that when the rod 41 is raised the blade 17 is off the contact 15 and the circuit is open. It is also apparent that this core 40 cannot be raised instantaneously, or practically instantaneously, because of the mercury in 50 38, so that this core acts as a plunger in a dashpot, in the tube 38. The device is so arranged and timed that it will be considerably slower than the action of the core 6 in the double solenoids 4 and 5, so that after the trolley wheel 30 is in place on the bars 12 and 13, as shown, the switchpoint is thrown, if any throwing is required, before
- the circuit can be opened through the action of the magnet 34. It will be noted that the circuit is closed through this magnet 34 just as long as the wheel 30 is on the bars 12 and 13, and the parts are so arranged and timed that the circuit will be open between parts 17 and 15 long before the magnets 4 or 5 can be burned out, so they are amply protected at all times.
- 70 The foregoing describes the structure and operation of the protecting device for the magnets 4 and 5. It is apparent that when the trolley wheel 30 is off the bar 13 the circuit through the magnet 34 is open, and then the switch 17 will fall on the contact 15 and again close the circuit at this point. This puts the apparatus in condition for the next operation.
- 75 When the wheel 30 reaches the short bar 32, a circuit is established through a wire 47 to a magnet 48 of the second cut-out 20, and from there a wire 49 runs to a resistance 50 which is placed therein, and from there to the ground 36. Assuming that the apparatus is in normal use, this causes the armature 21 to be drawn to the position shown in dotted lines, and then a circuit is established from the wire 9 through a wire 51 to a contact 52, armature 21, a second contact 53, thence through a wire 51 to one of the leads of the magnet 48, or the wire 47, so that the circuit is completed through the other lead and wire 49, as above described, so that as long as the armature 21 is in the position indicated in dotted lines, a circuit will be complete to the ground 36 from the wire 9, which is always alive as it is directly connected to the trolley wire 10. It will be understood that the armature 21, in the embodiment here shown, is pivoted at 55 and is provided with a counterweight 56 which always keeps it on the contacts 19 and 22 when the magnet 48 is not energized, as above described. Assuming the armature 21 to be in the position 90 shown in dotted lines, in Fig. 1, the circuit is opened between the contacts 52 and 53 in the following manner. When the trolley wheel 30 reaches the position indicated at 95 30^a where it is on the second trolley pan 57, 110 at that time one of the bars 58 gets electricity through a conductor 59 from the trolley wire 10, and the other bar 60 gets it through the trolley wheel, so that a wire 61 which is connected to the bar 60, receives 120 electricity and transmits it, as indicated, to the wire 49 just above the resistance, so that electricity can flow directly from the trolley wire through the parts above indicated and wire 61 to the ground 36, except for the 125 opposition of the resistance of the wire, which is small, and the resistance 50. This practically short-circuits the magnet 48 and renders it so that it cannot overcome the 130 opposition of the weight 56 and thereby

causes the circuit to open, as above indicated, so that the apparatus is restored to its normal and original condition, and is ready for the next operation, and then the 5 trolley wheel 30 passes along the trolley wire 10 and out of the device. It will be understood that the trolley pan 57 is placed substantially above and just before the switchpoint 7, so that the car will be through 10 the switchpoint 7 before the trolley wheel 30 enters the trolley pan 57.

In view of the foregoing, the operation of our improved switching device will be readily understood. It is obvious that under 15 normal conditions it will act precisely the same as the switching devices described in the above mentioned patents. If, however, the trolley wheel 30 remains too long on the bars 12 and 13, the circuit opener 16 20 will act, as above described, to protect the magnets 4 and 5, and when the car is again started the switchpoint 7 will not be shifted because the circuit is open between the parts 17 and 15. To prevent a car passing over 25 the switch from being interfered with by a following car it is obvious that the action of the second cut-out 20 is sufficient to open the armature circuit at a second point, and keep it open, until the trolley wheel 30 is 30 on the second trolley pan 57, when the device is restored to normal. Thereafter it is ready for an indefinite repetition of the cycles above described.

While we have shown and described one 35 embodiment of our invention, it is obvious that it is not restricted thereto, but may be modified in any of many ways, all of which come within the scope of our invention as set forth in the annexed claims.

40 Having thus described our invention, what we claim is:

1. In a system of the class described, a trolley wire with two trolley pans placed thereon and spaced apart, one of these trolley pans being placed so that a car passing under the same may have its trolley wheel engage it in time to operate a switch, and the second trolley pan so placed that the switch will be passed by the car before this second 45 trolley pan is engaged, a circuit controller, wires connecting the circuit controller with the first mentioned trolley pan, a double solenoid, a ground for said double solenoid, wiring connecting the double solenoid with the circuit controller, two circuit openers or cut-outs 50 and a ground for each, and wiring connecting said cut-outs with the said trolley pans so that one cut-out is connected with each, all of said parts being arranged and disposed so

that when in use the system always works 60 power on and power off the motors of a car using the same, and so that if this car stands too long in connection with the first trolley pan, a cut-out opens the circuit through the double solenoid, and so that when this car 65 leaves the first trolley pan, no succeeding car can energize a coil of the double solenoid until the first car has engaged the second trolley pan.

2. In a system of the class described, a 70 trolley wire with a trolley pan mounted thereon, a circuit controller, wiring connecting the trolley pan and circuit controller, a double solenoid, wiring connecting the circuit controller and double solenoid, a ground 75 for said double solenoid, a circuit opener, a ground for said circuit opener, a wire connecting said circuit opener with said trolley pan, and a second wire for connecting said circuit opener with said circuit controller, 80 all of said parts being so arranged and disposed that when in use the system always works power on and power off the motors of a car using the same, and so that if this car stands too long in connection with the 85 trolley pan the cut-out opens the circuit through the double solenoid and thereby prevents a coil of the double solenoid from being burned out.

3. In a system of the class described, a 90 trolley wire with two trolley pans spaced apart and placed thereon, one of said trolley pans being so placed that a trolley wheel will engage the same before the car to which the wheel is attached reaches a switch-point, 95 and the other trolley pan being so placed that this car will have passed the switch-point before its trolley wheel engages the second trolley pan, a circuit controller, wiring between the circuit controller and the 100 first mentioned trolley pan, a double solenoid, wiring between the double solenoid and the circuit controller, a ground for said double solenoid, a second ground and a cut-out connected to the second ground and the 105 trolley wire and both trolley pans, suitable wiring, all arranged and disposed so that when in use the system always works power on and power off the motors of a car using the same, the cutout being connected to the 110 two trolley pans so that when this car leaves the first trolley pan, no succeeding car can energize a coil of the double solenoid until the first car has engaged the second trolley pan.

ROBERT V. CHEATHAM.
ELMER S. OLMSTED.
